UNITED STATES PATENT OFFICE.

JOSEPH BEHLE, OF DALLAS, TEXAS, ASSIGNOR TO THE MURRAY COMPANY, OF DALLAS, TEXAS, A CORPORATION OF TEXAS.

LAMBREQUIN FOR COTTON GINS.

Application filed October 11, 1928. Serial No. 311,732.

This invention relates to new and useful improvements in lambrequins for cotton gins.

In the ginning of cotton it is customary to employ a toothed or comb-like bar at the bottom of the roll box just over the huller ribs to support the roll of cotton. Those lambrequins now in common use are usually made by driving steel pins into a previously bored pipe or rod, so that the pins extend at right angles to the longitudinal axis of the pipe or bar. Such pins break, bend and become loose, thus interfering with the operation of the gin.

One object of the invention is to provide a lambrequin with integral teeth or fingers formed in a new and novel manner and making for increased strength and more economical manufacture.

Another object of the invention is to provide a lambrequin with downwardly curved teeth, either in the form of integral teeth or the usual driven pins, overlying the huller ribs, whereby the seeds are more quickly released and the cotton is more rapidly handled, thus increasing the ginning capacity.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a partial transverse sectional view of a gin equipped with a lambrequin constructed in accordance with the invention,

Fig. 2 is an enlarged cross-sectional view taken on the line 2—2 of Fig. 4,

Fig. 3 is an enlarged cross-sectional view of one of the fingers,

Fig. 4 is a plan view of the lambrequin, and

Fig. 5 is a view similar to Fig. 1 showing the ordinary driven finger type of lambrequin equipped with curved fingers.

In reference to the drawings the numeral 10 designates a rib rail commonly used in gin stands for the purpose of supporting ribs 11, sometimes referred to as huller ribs, which when correctly spaced between a plurality of gin saws 12 mounted on a saw shaft 13 and held equidistant by spaced blocks 14 will remove from the cotton, that is pulled between

these ribs by the saws, all hulls and trash which flows into the gin.

55

After the cleaned cotton has passed the ribs 11, it is brought into contact with another set of ribs 15 which are spaced close enough to the saws to remove the seed from the cotton. These ribs are so shaped as to cause the cotton that is not pulled immediately therethrough, to roll on top of the saws.

It is customary to use a lambrequin and one of the ordinary type is shown in Fig. 5, except that it is equipped with curved fingers 17 and such fingers are not now in common use and constitute part of the invention. The lambrequin A is composed of a cylindrical head 16 having a plurality of curved fingers 17 driven therein which are particularly shaped to closely conform to the curved tops of the ribs 11, whereby these ribs not only support said curved fingers, but prevent them from bending or breaking. The curved fingers are very advantageous and are a new departure in the art.

Another and more improved form of lambrequin is shown in Fig. 4. The fingers 18 are made integral with the cylinder shaped head 19. These fingers are die-pressed or suitably formed so as to be curved longitudinally and U-shaped in cross-section as is illustrated in Fig. 3 so as to give them sufficient strength. Shanks 20 connect the fingers with the head 19 and are reinforced by ribs 21 which are pressed in these shanks and merge into the head. The shanks provide a substantial and rigid connection between the head and fingers and reduces the tendency of the fingers to break off.

90

The lambrequin is made from a suitable sheet of metal and the process of manufacture is as follows: a blank sheet of metal is cut the proper length and width. It is then placed in a press and the fingers and shanks with their reinforcing ribs are cut therefrom and formed. The partially formed lambrequin is then taken to a roller and the cylindrical head rolled. By this method a very crude means of manufacturing is eliminated.

95

The lambrequin as now commonly manufactured, is made of pipe or tubing. Holes evenly spaced are drilled in this pipe and fingers or pins driven therein. This process requires a considerable amount of time and labor. Thus it is evident that by forming the

105

fingers and head in two operations of a single sheet of metal a considerable amount of time and labor can be saved.

After the stamped lambrequin is formed 5 a core bar 22 is inserted in the head 19. This bar is held therein by any suitable means, such as rivets 23. The purpose of this bar is to strengthen the head and prevent it from bending as is the case with the old style lambrequin when the fingers or pins are driven 10 therein.

In applying this new type lambrequin to the roll box of a cotton gin it is quite evident 15 that many good results will be had. By curving the fingers downward the capacity of the gin is greatly increased because the saws will expose a greater surface to grasp the cotton and by this improvement the cotton can be handled faster for the reason that the seeds 20 will be removed quicker.

Another feature of this invention is that by the fingers being curved and overlying the tops of the huller ribs, all possibility of 25 them becoming bent or broken is practically eliminated. Further, lint cannot lodge between the fingers and the huller ribs.

Various changes in the size and shape of the different parts, as well as modifications and alterations, may be made within the scope 30 of the appended claims.

What I claim, is:

1. A lambrequin for cotton machinery including a plurality of curved fingers.

2. A lambrequin for cotton machinery including a plurality of downwardly curved fingers.

3. The combination with the huller ribs and roll box of a cotton gin, of a lambrequin mounted at the bottom of the roll box and including a plurality downwardly curved fingers overlying said huller ribs.

4. The combination with the huller ribs and roll box of a cotton gin, of a lambrequin mounted at the bottom of the roll box and including a plurality downwardly curved fingers overlying said huller ribs, said fingers being curved contiguously to the huller ribs.

5. A lambrequin for cotton machinery including a longitudinal head and fingers

formed from the same sheet of metal as the 50 head and extending from the head, said fingers being curved downwardly.

6. A lambrequin for cotton machinery comprising an elongated cylindrical head and extended fingers, all cut and formed from a 55 single sheet of metal, said fingers being U-shaped in cross-section and curved downwardly.

7. A lambrequin for cotton machinery including a longitudinal cylindrical head, a core bar inserted in the head, and fingers 60 merged from the head and curved downwardly therefrom and formed integral therewith.

8. A lambrequin for cotton machinery including a cylindrical elongated head, finger shanks bent from one side of the head, fingers 65 extending from the shanks and into which the shanks are merged, said fingers being U-shaped in cross-section, and reinforcing ribs 70 pressed in the shanks and extending from the fingers to the head.

9. A lambrequin for cotton machinery comprising an elongated cylindrical head and fingers extending from one side of the head 75 and cut from the same sheet of metal, the fingers having flaring shanks merging into the head.

10. A lambrequin for cotton machinery comprising an elongated cylindrical head and fingers extending from one side of the head 80 and cut from the same sheet of metal, the fingers being U-shaped in cross-section.

11. A lambrequin for cotton machinery comprising an elongated hollow cylindrical 85 head and fingers extending directly from the head and substantially tangentially therefrom, the head and fingers being formed in one piece.

12. A lambrequin for cotton machinery 90 comprising an elongated cylindrical head and fingers extending from one side of said head, the fingers and head being formed of one piece of metal, and a core extending through the head and secured therein for reinforcing the lambrequin.

In testimony whereof I affix my signature.

JOSEPH BEHLE.
